CLAIM

The ornamental design for a travel press, as shown and described.

DESCRIPTION

FIG. 1 is a perspective view of a travel press showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a sectional view taken along line 8-8 of FIG. 6; and, FIG. 9 is an enlarged top perspective view of the travel press broken away for ease of illustration.

The broken lines in the drawings are included for the purpose of illustration and form no part of the claimed design.
